UNITED STATES PATENT OFFICE.

JAMES ARTHUR CLARK, OF HERKIMER, NEW YORK.

PAPER-CUTTING ATTACHMENT FOR PAPER-BOX-COVERING MACHINES.

SPECIFICATION forming part of Letters Patent No. 392,313, dated November 6, 1888.

Application filed March 23, 1886. Serial No. 196,276. (No model.)

To all whom it may concern:

Be it known that I, JAMES ARTHUR CLARK, a citizen of the United States, residing at Herkimer, in the county of Herkimer and State of New York, have invented a new and useful Improvement in Paper-Cutting Attachments for Paper-Box-Covering Machines, of which the following is a specification, reference being had to the accompanying drawings.

My invention relates to an improvement in paper-cutting attachments for paper-box-covering machines; and it consists in the peculiar construction and combination of devices, that will be more fully set forth hereinafter, and particularly pointed out in the claims.

In the drawings, Figure 1 is a perspective view of my invention. Fig. 2 is a vertical sectional view of the same, taken on the line xx of Fig. 1. Fig. 3 is a similar view taken on the line yy of Fig. 1. Figs. 4 and 5 are detail views.

I have herein shown and particularly described only the box-machine head provided with my improvements, omitting the remainder of the paper-box-covering machine, which is of the usual well-known construction, and forms no part of my present invention.

A represents the box-machine head, which is provided on its upper side, near one edge, with a pair of parallel vertical flanges, B, which are grooved on their opposing faces, as at C.

D represents a slide, which is provided on its under side, near one end, with a depending flange or shoulder, D', which works between the flanges B, and vertically through an opening which is made in the said slide passes a set-screw, D², having a broadened head at its lower end, which fits in the grooves C, and its upper end provided with a thumb-nut, by means of which the slide may be tightened on the flanges (which form a guideway) at any desired adjustment on the machine. From the outer end of the slide B projects a vertical standard, E, to which is secured a vertically-adjustable block, F, by means of a set-screw, f, which binds against the standard. To one end of the block F is rigidly secured the lower jaw, G, of a pair of shears by means of screws g, the cutting-edge of the said jaw G project-

ing at right angles from one side of the machine-head and in a horizontal line.

H represents a pivotal bolt, which passes horizontally through an opening that is made 55 in the block F and forms a fulcrum for the upper pivoted cutting-jaw, G'. On the threaded end of the bolt H is placed a circular spring-plate, I, having notches cut in its periphery, and thereby forming radial arms which bear 60 against one end of the block F, and nuts h and h' are screwed on the threaded end of the bolt H and bear against the plate I, so as to force the latter with any desired degree of pressure against the block F, and thereby keep the jaw 65 G' firmly pressed against the lower jaw, G.

On the upper side of the head A, at one end, is secured a bearing-block, A', in which is journaled a transverse shaft, K. Near one end of the said shaft, and between the side walls of the 70 head, is secured a gear-wheel, K', which is adapted to gear with a driving gear-wheel, forming a part of the paper-box-covering machine, in order to rotate the shaft K. One end of the said shaft extends outwardly for a suitable distance beyond the front side of the machine-head, and to the said shaft is secured a circular disk, L, in proximity to the front side of the machine. Projecting from the rim of this disk is a tappet-arm, L', and near the rim 80 of the disk is made a transverse opening, through which passes a stud, L², the outer end of which projects normally beyond the outer face of the disk L.

M represents a flat spring, which has one 85 end secured to the rear side of the disk by means of a screw, M', and near the outer end of the said spring is made a slot, m, through which passes a screw, m', that enters the rear end of the stud L², and thereby secures the 90 said stud to the free end of the spring. The function of the latter is to keep the stud L² normally pressed outwardly beyond the outer face of the disk. The outer end of the spring M is provided with a projection, M², which extends radially from the rear side of the disk 95 and is inclined at a slight angle therefrom.

N represents a disk, which is journaled loosely on the projecting end of the shaft K, and is provided near its rim, on one side, with an opening, N', to receive the projecting end of the stud L², and communicating at one end with 100

the said opening, on the inner face of the said disk, is a concentric groove, N^3 , which is of suitable length. The inner face of the disk N bears normally against the opposing outer face of the disk L , and the stud L^2 normally projects through the opening N' in the said disk N . The latter is provided on its outer side with a projecting sleeve, N^4 , which is threaded for a suitable distance from its outer end, and thereby adapted to receive and secure the form upon which the paper box is to be placed. This form is represented in Figs. 1 and 3 by dotted lines, and is not more fully described here for the reason that it is of the well-known usual construction. The outer end of the shaft K is provided with a reduced threaded spindle, K^2 , on which is screwed a nut, K^3 , which bears against the outer end of the sleeve of the disk N , to prevent the latter from moving laterally on the shaft and causing its inner face to always bear against the opposing face of the disk L .

The box-form has an opening through which the threaded sleeve passes, and on the said sleeve is a hand clamping-nut, Z , which bears against the outer side of the box-form and secures the same firmly in place upon the sleeve.

On the front side of the head A is secured a bracket, O , which is provided with an outwardly-extending horizontal upper arm, O' , the outer end of which projects beyond the rim of the disk L and just clears the said disk. On the side of the said arm, adjacent to the disk, is made a groove, O^2 , at an angle of about thirty-five degrees from the perpendicular, thereby forming a cam, O^3 , on the outer end of the said arm, to engage with the projection M^2 of the spring M once during every revolution of the shaft K .

P represents a rock-shaft on the front side of the head A and arranged horizontally thereon, one end of the said shaft being journaled in an offset at one end of the head and the other end of the said shaft being journaled in the arm O' . Rigidly secured to one end of the rock-shaft is an arm, P' , which bears against one side of the arm O' of the bracket, and projects outwardly from the rock-shaft in the path traversed by the tappet-arm L' . The rock-shaft is provided on one side with a spline, P^2 , which extends the entire length of the shaft, and engages an arm, R , which projects from the rock-shaft substantially in a line with the arm P' , the said arm R being thereby feathered on the said shaft and movable thereon.

S represents a pitman, one end of which is connected to the outer end of the arm R by means of a screw, R' , and the upper end of the said pitman is provided with a series of openings, S^2 , through one of which projects a threaded stud, G^2 , which extends from the rear end of the jaw G' and thereby connects the latter to the pitman. A thumb-nut, G^3 , is screwed onto the outer end of the stud G^2 , to prevent the pitman from slipping off the said stud. By providing the series of openings for the pit-

man it will be readily understood that the jaw G' may be secured thereto at any desired adjustment, and thereby regulate the stroke of the said jaw.

From the end of the rock-shaft opposite the arm P' projects an arm, T , which is secured on the said shaft, and the lower end of the said arm is connected to the lower front side of the head A by means of a coiled retractile spring, U .

The paper used to cover the box passes from the roll on the machine and through the gumming apparatus thereon, (which applies glue to the under side of the paper,) out between the jaws of the shears (bearing on the horizontal edge of the jaw G) to the box on the box-form. When the shaft K is rotated the box-form is turned, thereby causing the paper to cover the sides of the box. By the time that the tappet-arm L' reaches the under side of the arm P' the box is covered, and it only remains to sever the paper. Continued rotation of the shaft K causes the arm L' to move the arm P' upwardly, and thereby partly rotate the rock-shaft against the tension of the spring U , and cause the jaw G' to descend on the upper side of the paper, thereby causing the shears to sever the paper, as will be very readily understood. While the jaws are in the act of cutting the paper it is necessary that the box-form should remain stationary, and for this purpose I have devised the disk N , the engaging-stud projecting from a disk, L , the spring for actuating the stud, and the cam for moving the spring, hereinbefore described. The instant that the tappet-arm L' engages with the arm P' of the rock-shaft to actuate the cutting-shears the projection M^2 of the spring also engages the lower inclined face of the cam O^3 . As the said projection travels up on the inclined face of the said cam, and while the jaw G' is in its initial movement, the action of the cam on the spring forces the free end of the latter from the rear side of the disk L , thereby withdrawing the outer end of the stud L^2 from the opening N' in the disk N , and causes the said stud to work in the concentric slot N^2 on the inner face of the disk N , and thereby permit the said disk, and consequently the box-form carried by the said disk, to remain stationary on the shaft K while the latter is moving through a portion of its rotation, and while the jaw G' is descending in the act of cutting the paper from the box.

When the engaging end or projection of the spring M clears the cam O^3 , the stud L^2 remains in the concentric slot N^2 at the end thereof farthest removed from the opening N' . The attendant, in the act of affixing the free end of the severed strip of paper to another box which has replaced the finished end on the box-form, rotates the disk N far enough to cause the stud L^2 to traverse in a retrograde direction the slot M^2 and again engage the opening M' , and thereby lock the disk N firmly to the disk L , when the operation is proceeded with as before.

The function of the guideway B on the machine-head and the slide D engaging therewith and carrying the shears is to permit the latter to be adjusted laterally toward or from 5 the box-form, and thereby adapt the shears to operate when covering boxes of any size. By providing the standard E and making the block F, which carries the shears, vertically adjustable on the said standard the shears 10 may be adjusted vertically to accommodate different-sized boxes that are being covered, and by providing the pitman connecting the jaw G' with the rock-shaft with the series of openings the jaw G' may be so adjusted as to 15 cause it to swing through any desired segment of a circle, and thereby regulate the cut or shear of the jaws to the width of the strip of paper to be severed.

The function of the spring U is to return 20 the jaw G' to its normal position when the tappet-arm disengages the arm P' of the rock-shaft.

Having thus described my invention, I 25 claim—
1. In combination with the mechanism, sub-

stantially as described, for rotating the box-form of a paper-box-covering machine, the adjustable slide D, the standard E, connected to the slide, the shears vertically adjustable on the standard, and connections, substantially 30 as described, between the shears and the mechanism which rotates the box-form, as set forth.

2. The combination, in a paper-box-covering machine, of the rotating shaft K, carrying the box-form, the laterally-adjustable vertical standard E, the shears vertically adjustable on the said standard and having the rigid jaw G and the pivoted jaw G', for cutting the paper when the box is covered, and means, substantially as described, connecting the shaft 35 K with the pivoted jaw to operate the latter automatically at each rotation of the shaft, substantially as set forth.

In testimony that I claim the foregoing as my own I have hereto affixed my signature in presence of two witnesses.

JAMES ARTHUR CLARK.
